UNITED STATES PATENT OFFICE

MILTON W. POWELL, OF BALTIMORE, MARYLAND

CAR WHEEL

Application filed June 18, 1924, Serial No. 720,749. Renewed August 17, 1929.

The invention relates to railway car brakes and has as an object the provision of a brake which will act upon the wheel at a point other than the tread of the wheel. An additional object is the provision of a brake which will be more efficient than the brakes now in use by providing pressure upon a large proportion of the circumference of the drum to which it is applied.

10 An added object of the invention is the provision of a brake having readily renewable friction elements.

An illustrative embodiment of the invention is shown in the accompanying drawings, in which

Fig. 1 is an illustration from the inside of a car wheel with the axle shown in section and with the connecting rods broken away.

Fig. 2 is a plan view.

Fig. 3 is an exploded perspective view.

The car wheel 10 shown is or may be of the usual form. A brake drum 11 is shown upon said wheel and is preferably cast integral therewith. Removable surface elements 12—13 are shown as applied to the drum member 11 and fastened thereto by keys 12^a and 13^a and with the member 11 making up a complete brake drum 14. The details of the removable elements 12—13 are shown and claimed in an application filed by myself of even date herewith, Serial Number 720,750, now Patent No. 1,604,852 dated October 26, 1926.

To apply braking friction to the drum 14 a brake band is shown comprising straps 15—16. One end of strap 15 is shown with a projection 17 pivotally hung to a bracket 18 as at 19. The end of the strap 16 is shown pivoted at 20 to the end of the strap 15. The opposite end of the strap 16 is outwardly curved and provided with a pivot 21, which pivot is connected by a link 22 to a lever 23 by means of a pivot 24. The end of the lever 23 is pivotally connected at 25 to the strap 15 at one end, and at 26 to the brake rod 27 at its other end. Pull upon the brake rod 27 will therefore pull the strap 15—16 toward the drum 14 with great force.

Friction is produced against the drum 14

by means of shoes 28, each formed upon the arc of a circle to fit the surface of the drum and as shown, each being formed with a channel 29 in its outer surface in which the strap 15 may lie. To secure the shoes 28 to the straps 15 and 16 each shoe is provided with a projection 30 adapted to pass through an opening in the strap, the projection having an opening 31 through its end. A spring 32 may be slipped through the opening 31 in each projection 30. The ends of the springs are shown as provided with curved surfaces 33 adapted to seat in recesses 34 in the straps to retain the springs in place. To remove the shoes 28 the spring 32 which secures it in place must be flexed until the surface 33 can slip over the ridge 35 adjacent the recess 34, when the spring may be slipped circumferentially and removed from the opening 31 in the projection 30.

As an added means to prevent circumferential movement of the shoes 28 upon the straps 15—16 each shoe is provided with recesses 36 adapted to fit over projections 37 upon the strap 15 or 16. Preferably two sets of recesses and projections are supplied upon each shoe element 28.

When the parts become worn either the surface elements 12—13 may be renewed, or one or all of the shoe elements 28 without requiring the application of an entire new car wheel to the axle or, as is the usual practice, an entire new axle with two new wheels attached. The brake band disclosed which completely surrounds the drum and applies pressure through a plurality of surfaces about the surface of the drum, which surfaces together make up a large proportion of the circumference of the drum, provides a very efficient braking action. In addition the strains on the brake drum are entirely self-contained so as to be more efficient than the usual form of brake upon railway cars.

I claim as my invention:

A brake mechanism for car wheels, comprising in combination a car wheel, an axle therefor having cast integral thereon a brake drum, removable surface elements applied to said drum, a pivoted brake band comprising sections surrounding said drum, removable

shoes carried by the sectional brake band, operating levers to control the movement of said bands, and a removable means to secure said shoes to said bands and to hold said shoes against lateral movements.

5 In testimony whereof he hereunto affixes his signature.

MILTON W. POWELL.
